UNITED STATES PATENT OFFICE.

CHARLES JEENS GRACE, OF TRURO, ENGLAND.

CARBURETER.

1,274,709.

Specification of Letters Patent.

Patented Aug. 6, 1918.

Application filed June 3, 1916. Serial No. 101,562.

To all whom it may concern:

Be it known that I, CHARLES JEENS GRACE, a subject of the King of Great Britain, residing at Tregrayth, Kenwyn, Truro, in the county of Cornwall, England, have invented new and useful Carbureters, of which the following is a specification.

This invention relates to improved means for carbureting air and for regulating the supply of liquid fuel to internal combustion engines in which liquid fuel is delivered by a number of capillary tubes.

According to this invention an assemblage of the capillary tubes is so arranged and bodily shifted that the number of tubes in action can be varied to regulate the supply of fuel. A number of capillary tubes are carried in a frame, or a block is pierced with a number of capillary tubes, the frame or block being so arranged that the undersides of the capillary tubes dip into a reservoir of liquid fuel, the number of tubes in action being varied to control the amount of fuel delivered.

Preferably the frame or block is located in the air supply passage so that the air supply to the engine is regulated by moving the frame or block, and the capillary tubes are of such a length that the amount of fuel delivered diminishes as the air supply is shut off, so as to give a mixture of constant proportions.

The block may be cast with a number of wires in it which are afterward withdrawn leaving capillary tubes, or the block may consist of a number of tubes of glass or other vitreous material packed in a suitable matrix to form the block, and the tubes are such that the liquid fuel is raised by capillary action at least 3/8ths of an inch.

The drawings illustrate apparatus made in accordance with my invention. Figure 1 is a section and Fig. 2 is an elevation partly in section at right angles to Fig. 1 in which the capillary tubes are carried in a frame. Fig. 3 is a block which may be used in place of the frame carrying the capillary tubes.

Capillary tubes *a* of varying length are carried by a frame *b* secured to the cover *c*

of a liquid fuel receptacle *d*. The cover *c* has trunnions *c' c'* connected by links *e e* to cranks *f f* on a shaft *g*, so that when the shaft *g* is turned, the cover *c* and frame *b* are raised or lowered. In the receptacle *d* is a float *h* operating an inlet valve *i* in the usual manner. *k k* are air inlets and *l* is a passage by which the air and fuel pass to a combustion chamber. The passage *l* may be closed by a disk *m* on the shaft *g*. It will be observed that the frame *b* is shown in the drawings in its lowest position and therefore at the point of the maximum immersion of the tubes *a* and the passage *l* is fully opened. When the shaft *g* is turned, some of the tubes *a* are raised out of the liquid fuel so that less fuel is supplied and at the same time the tubes *a* enter the mouth of the passage *l* constricting the air supply.

The block shown in Fig. 3 is pierced with capillary tubes indicated by dotted lines *n* and is carried by the cover *c* in a similar manner to the frame *b*.

It will be noted that the cluster of tubes is moved bodily relatively to the fuel and that each tube has direct independent communication with the fuel when it is dipped into the fuel. When a given tube is not within the body of fuel it is not effective to conduct the fuel by reason of suction. Thus it is apparent that my tubes operate, or cease operating, by their bodily movement into and out of the fuel as distinguished from structures in which the tubes are constantly in communication with a fuel receptacle and are successively turned to receive fuel, or are stationary and governed by a movable valve.

What I claim is:

In a carbureter, a fuel receptacle, a cover for said receptacle, means for moving the cover, an assemblage of capillary tubes carried by the cover and adapted to deliver liquid fuel, an inlet for the air, and an outlet for the mixture of fuel and air located in the path of the capillary tubes when the cover is moved.

CHARLES JEENS GRACE.

Copies of this patent may be obtained for five cents each, by addressing the "Commissioner of Patents, Washington, D. C."
